UNITED STATES PATENT OFFICE

WILLIAM H. GRAVES, OF CULVER CITY, CALIFORNIA

DESIGN FOR A SANDAL

Application filed May 16, 1932. Serial No. 43,822. Term of patent 14 years.

To all whom it may concern:

Be it known that I, WILLIAM H. GRAVES, a citizen of the United States, residing at Culver City, in the county of Los Angeles, State of California, have invented a new, original, and ornamental Design for Sandals, of which the following is a specification, reference being had to the accompanying drawing, forming part thereof.

The figure is a perspective view of the sandal, showing my new design.

I claim:

The ornamental design for a sandal substantially as shown.

WILLIAM H. GRAVES.
